SPECTACLE PROTECTOR

Theo J. Sowle, Grand Rapids, Mich.

Application May 21, 1951, Serial No. 227,480

1 Claim. (Cl. 2—9)

This invention relates to spectacle protectors and, in particular, to such protectors as are used by athletes in sports, games and the like.

One object of this invention is to provide a spectacle protector which is quickly and easily adaptable to different sizes of heads of wearers, without requiring different sizes of protectors.

Another object is to provide a spectacle protector wherein a semi-rigid frame or cage composed of vertical and horizontal guard bars forming a cage-like structure is attached to a head gear and has attached to it a chin strap which increases the rigidity of the protector and prevents it from being knocked aside by blows or brushes with opponents during games, such as basketball, with consequent damage to the spectacles.

Another object is to provide a spectacle protector of the foregoing character wherein the frame or cage has retaining bars adjacent the ears of the wearer which will press firmly against the temples or bows of the spectacles and hold them firmly in their correct position.

Another object is to provide a spectacle protector of the foregoing character wherein the frame or cage is attached by clips to a simple head gear which is lighter and less expensive to produce and which is also cooler during wear.

Another object is to provide a spectacle protector of the foregoing character wherein the head gear has a simple and rapid adjustment for fitting the head gear to different sizes of heads located at the back of the head where the head straps converge toward one another.

Other objects and advantages of the invention will become apparent during the course of the following description of the accompanying drawings, wherein:

Figure 1 is a side elevation of a spectacle protector according to one form of the invention, as fitted to a wearer's head, shown in dotted lines;

Figure 2 is a front elevation of the spectacle protector shown in Figure 1, with the location of the spectacle lenses shown in dotted lines;

Figure 3 is a front perspective view of the frame or cage of the protector, with the head gear and chin straps removed;

Figure 4 is a fragmentary bottom plan view of the portion of the chin strap beneath the chin; and

Figure 5 is an enlarged fragmentary side elevation of the chin strap buckle and protecting pad.

Referring to the drawings in detail, Figures 1 to 3 inclusive show a spectacle protector, generally designated 10, as consisting generally of a head gear 11 to which a protector frame or cage 12 is attached, the cage in turn having a chin strap, generally designated 13 attached thereto. The head gear 11 consists of a top strap 14 which goes over the top of the head H and a side strap 15 which goes entirely around the sides of the head and which is secured to the forward end of the top strap 14, as by stitching 16. The rearward end or ends of each of the straps 14 and 15 is provided with a loop member 17, 18 or 19 (Figure 2) consisting of a short strip of leather

2

or other suitable material which is bent back upon itself, and the opposite ends stitched or otherwise secured to the end of the particular strap to which it is connected. The free end or nose portion of the loop member 17, 18 or 19 is tapered as at 20, 21 or 22. An elastic cord 23 is threaded through the ends 20, 21 and 22 and tied in a knot as at 24 while the head gear 11 is on the wearer's head.

Riveted or otherwise secured to the front and sides respectively of the side strap 15 of the head gear 11 are three clips, namely a front clip 25, and 2 side clips 26 (Figure 2) which are also of loop shape formed by doubling a strip of metal back upon itself, the cage or protector frame 12 being secured to these clips. The side clips 26 are located on the side band 15 a slight distance forward of the wearer's ears E. The frame or cage 12 consists of upper and lower frame members 28 and 29, each of approximately U-shaped form connected to one another by approximately vertical connecting or retaining portions 30 at the rearward ends thereof. The upper and lower members 28 and 29 have parallel approximately horizontal front members 31 and 32 interconnected by vertical frame members or struts 33, three being shown for purposes of convenience.

In order to cause the connecting or retaining portions 30 to press against the spectacle temples T, the upper and lower members 28 and 29 are preferably bent at slightly less than right angles to one another at their upper and lower corners 34 and 35 (Figure 3) and form upper and lower side members 36 and 37 respectively 30 interconnected by vertical side frame members or struts 38, in addition to the connecting portions 30 at their rearward ends. The frame members 33 and 38 are connected as by welding to the frame members 28 and 29. The side portions 36 of the upper frame member 28 are substantially horizontal as at 39 for the major portion of their length but are inclined downwardly as at 40 near their rearward ends adjacent their junction with the connecting portions 30. The lower side members 37, on the other hand, have upwardly and rearwardly inclined portions 41 and 42 located on opposite sides of each vertical member 38. Near their rearward ends, however, the upwardly inclined portions 42 are bent abruptly downward to provide downwardly inclined portions 43, and these in turn are connected by approximately horizontal portions 44 which are inclined slightly upward and rearward toward their junction with the connecting portions 30.

Secured as by welding to the front portion 31 of the upper frame member 28 are the lower opposite ends of an approximately arch-shaped frame member 45 having arcuate arms 46 bent upward and rearward in an inclined direction (Figure 1) to a junction with an approximately U-shaped central portion 47 which has side portions 48 and a rearward portion or cross bar 49. The cross bar 49 passes through the opening in the loop-shaped front clip 25, whereas the inclined portions 40 of the upper side members 36 pass through the loop-shaped side clips 26.

The chin strap 13 is provided with a loop 50 formed on one end of a non-adjustable strap 51 of webbing, leather or the like, the loop 50 being passed around one of the lower frame portions 44 and secured by stitching or riveting. The free end of the strap 51 is provided with a snap fastener 52 (Figures 2 and 4), the cooperating element 53 of which is secured to a chin pad 54 of leather or other suitable material. The provision of two or more of the elements 53 provides a quick adjustment of length for the chin strap 13. Secured as by stitching to the chin pad 54 is the lower end of an adjustable strap 55 also of webbing or leather. The upper end of the strap 55 is secured by riveting or stitching to a perforated tongue strap 56 of leather or other suitable material which passes

through a buckle 57, the cross bar 58 of which (Figure 5) passes through a loop member 59 of leather or other suitable material through which also passes the portion 44 of the lower frame member 29 opposite the portion 44 to which the loop 50 was attached. The upper ends of the loop member 59, which is formed of a strip of leather or other suitable material bent back upon itself, are secured to each other and to the upper end of a protector pad 60 of leather or other suitable material which protects the face from direct contact with the buckle 57. The lower end of the pad 60 is left free and protects the face from contact with the rivet or other fastener used in securing the strap 55 to the tongue strap 56.

In order to cushion the contact of the connecting portions 30 with the bows or temples T of the wearer's spectacles S, each of the connecting portions 30 is surrounded by a tubular member 61 of leather, rubber or other suitable cushioning material.

In the adjustment of the invention, the user first adjusts the head gear 11 approximately to the size of his head, tying the elastic cord 23 as at 24 when this adjustment has been made. A single adjustment of the elastic cord 23, because of the resilience of the cord, enables the head gear 11 to fit a range of sizes of heads. The user then adjusts the chin strap 56 to the correct approximate length by inserting the tongue of the buckle 57 through the most desirable hole in the tongue strap 56. The snap fastener 52, 53 is used thereafter in putting on and taking off the spectacle protector 10.

In the use of the spectacle protector 10, while playing games such as basketball, the cage or frame 12 completely protects the lenses L of the spectacles S from damage from any source, either from opponents or from the ball, or from collisions with stationary objects, such as walls or stanchions. The cushions 61 and connecting portions 30 press inwardly against the temples or bows T of the spectacles S adjacent the point where these pass around the ears E of the wearer's head H.

What I claim is:

A spectacle protector comprising, a skeleton head gear structure adapted to snugly fit the head and having a side strap for encircling the head at approximately the place of maximum diameter thereof, and having free ends closely approaching but spaced apart from one another at the rear of said head gear structure, said head gear structure also having a single top strap adapted to fitting over the top of the head, said top strap having one end secured to said side strap at the front of said gear structure and a free end closely approaching but spaced apart from the free ends of and from the space between said side straps at the rear of all of said head gear structure, said free ends having apertures therein, an elongated flexible elastic cord having a loop portion passing through said apertures and adjustably and slidably engaging and interconnecting said free strap ends, said cord being adapted to be selectively tied at different locations for providing different sizes of said loop portion whereby to effect different separations of said strap ends to fit different head sizes, the resiliency of said cord causing said straps to snugly and yieldingly grip a particular size of head, the sole connection of said free ends with one another being through said resilient cord when used as a tying element, said free ends being otherwise disposed independent of one another, a protector frame structure having front and side portions secured respectively to the front and sides of said head gear structure, and a chin strap secured at its opposite ends to said structure and adapted to extend under the chin of the wearer.
